C. S. MORSE,
METHOD AND MEANS FOR BILLET CASTING,
APPLICATION FILED JUNE 30, 1920.

1,387,292.

Patented Aug. 9, 1921.

UNITED STATES PATENT OFFICE.

CHARLES S. MORSE, OF ROLAND PARK, MARYLAND, ASSIGNOR TO BALTIMORE TUBE COMPANY, INCORPORATED, A CORPORATION OF VIRGINIA.

METHOD AND MEANS FOR BILLET-CASTING.

1,387,292.

Specification of Letters Patent. Patented Aug. 9, 1921.

Application filed June 30, 1920. Serial No. 392,993.

To all whom it may concern:

Be it known that I, CHARLES S. MORSE, a citizen of the United States, residing at Roland Park, in the county of Baltimore, 5 State of Maryland, have invented a new and useful Method and Means for Billet-Casting, of which the following is a specification.

My invention relates to billet casting. The 10 object is to provide improved method and means for casting hollow billets. The invention comprises improvements in the invention described in my copending application filed June 8th, 1920, Serial No. 15 387,348.

The invention comprises a mold and a co-operating tapered core, and means for causing a relative movement between the mold and the core during the operation of pouring 20 into the mold.

In the example shown the core is held stationary and the mold is moved upwardly, in the direction of the taper of the core, during the pouring operation. The movement 25 of the mold and the operation of pouring may be so timed and related, that the top of the mold shall pass the top of the core before the completion of the pouring operation.

30 Referring to the drawings, which illustrate merely by way of example suitable means for effecting my invention:—

Figure 1 is a view, in part elevation and part vertical section, of means for effecting 35 my invention.

Fig. 2 is a fragmentary sectional view of the upper part of the mold, showing the core and mold in relative positions at the end of the casting operation.

40 Fig. 3 is a fragmentary sectional view of the upper end of the casting.

Fig. 4 is a horizontal section on the line 4—4 of Fig. 1.

Similar numerals refer to similar parts 45 throughout the several views.

The mold element 6 is shown mounted in the trunnion member 7, having trunnions 7 adapted to be supported by the bracket 8, connected with the mold table or platform 9, mounted on the hydraulic plunger 10 operating in cylinder 11.

The core element 12 is provided with the extension 13 secured in the portion 14 of the stationary framework, so that said core ele-

ment 12 is supported on the stationary base 55 or portion 14 and held in position by the pin 15 or other suitable means. This core is shown as tapering upwardly.

At the upper end of mold member 6 is removably mounted the pouring funnel 16. At 60 the lower end of mold element 6 is provided the print or removable block 17 secured in position by the bolt 18. This block 17 is adapted to fit snugly around the base or larger end of core 12 when in initial position.

In operation the caster may stand upon the table or platform 9, while pouring into funnel 16. This table or platform 9, also provides a convenient supporting means 70 for the ladle or other suitable pouring device, not shown, so that said supporting means shall move with the moving mold. As the pouring begins, pressure is admitted to the hydraulic cylinder 11 to move the plunger 10 upwardly, which carries platform 9 and the mold 6 upwardly relatively to the core 12.

As stated in my said copending application, the molten metal coming in contact 80 with the cooler walls of core 12 becomes sufficiently set as to its inner skin or wall to hold the metal as the mold moves upwardly into regions where the cross sectional dimension of the core is reduced. 85

If so desired, the relative movement between the plunger 10 and mold 6 may be so timed, with respect to the pouring operation, as to bring the top of the core 12 into the position shown in Fig. 2, at approximately 90 the point of completion of the pouring operation, so that the metal will cover the end of core 12 and leave the casting closed at its top, as shown in Fig. 3. This form of casting being desirable for cupping purposes. 95

It will be understood that the specific device, as illustrated in the drawings and described in this specification, is only given as an example, and that other forms of 100 apparatus may be used for effecting my invention, as defined in the following claims.

What I claim is:—

1. The method of casting hollow billets, which consists in introducing the molten 105 metal into the space formed between a mold element and a separable core element and moving the mold element relatively to the

core element to cause the withdrawal of the core from the mold during the pouring operation.

2. The method of casting hollow billets, which consists in introducing the molten metal into the space formed between a mold element and a separable tapered core element and moving the mold element relatively to the core element to cause withdrawal of the core from the mold during the pouring operation, the degree of taper of the core element and the speed of the movement of the mold element being relative to the degree of contraction of the metal of the casting in the process of cooling.

3. The combination of a mold element, a coöperating core element, and means for moving the mold element relatively to the core element to cause the withdrawal of the core from the mold during the pouring operation.

4. The combination of a mold element, a coöperating core element, means for moving the mold element relatively to the core ele-

ment, during the pouring operation, and a platform forming a part of the mold support and moving with the mold element.

5. The combination of a mold element, a coöperating core element, means for moving the mold element relatively to the core element, during the pouring operation, and a supporting platform for carrying the operator moving with the moving mold element.

6. The combination of a mold element, a coöperating core element, means for moving the mold element relatively to the core element, during the pouring operation, and a platform adapted to move with the mold element.

7. The combination of a mold element, a coöperating core element, and means for moving the mold element relatively to the core element, simultaneously with the pouring operation, said means comprising a cylinder for a pressure medium and a plunger operating therein.

CHARLES S. MORSE.
